UNITED STATES PATENT OFFICE.

FRANCIS H. RICHARDS, OF SPRINGFIELD, MASS., ASSIGNOR TO THE AMERICAN BUTTON FASTENER COMPANY, OF NEW BRITAIN, CONN.

BUTTON-SETTING MACHINE.

SPECIFICATION forming part of Letters Patent No. 326,786, dated September 22, 1885.

Application filed January 30, 1885. (No model.)

To all whom it may concern:

Be it known that I, FRANCIS H. RICHARDS, a citizen of the United States, residing at Springfield, in the county of Hampden, State 5 of Massachusetts, have invented certain new and useful Improvements in Button-Setting Machines, of which the following is a specification, reference being had to the accompanying drawings, in which—

10 Figure 1 is a plan view of a machine embodying my improvements. Fig. 2 is a front elevation of the same machine. Fig. 3 is an elevation of the right-hand side. Fig. 4 is a rear elevation. Fig. 5 is a horizontal section of the front part of the machine, in line *a a*, Fig. 2. Figs. 6, 7, 8, 9, 10, and 11 are vertical sections in line *b b*, Fig. 5. Figs. 12, 13, and 14 illustrate the action of the fabric-feeding mechanism. Fig. 15 shows three views of 20 the fastener driver and slide. Fig. 16 shows three views of the fastener-bender, and Fig. 17 of the fastener-former pin. Fig. 18 shows four views of the button-feeding slide, Fig. 19 of the button-tube, and Fig. 20 of the button-receiver. Fig. 21 shows three views of the button-feeding spiral. Fig. 22 is an enlarged view of 25 certain parts of said spiral. Fig. 23 illustrates the operation of the spiral under certain circumstances.

30 Similar reference characters refer to similar parts throughout the views.

My invention relates more especially to improvements in machines for automatically making and setting button-fasteners, although 35 some parts thereof are adapted to be used in similar machines which are not automatic.

The principal object of the invention is to provide a machine which shall feed the buttons from a hopper to the setting-die, hold and 40 feed the fabric under said die, and automatically make and set the fasteners for holding the buttons to the fabric. Another object is to provide improved devices for performing those operations.

45 The invention consists in an organized machine of the class described and in the devices and combinations embodied therein which are hereinafter described and claimed.

In the drawings, A designates the bed-plate 50 of the machine, which is supported on legs A², and from the top of which rise the two

uprights A³ and A⁴ for supporting the more essential parts of the machine. Bearings are formed in legs A² for the main shaft S, which is driven by means of pulley P, and carries 55 the several cams, the pulleys P² and P⁴, and the worm G² for communicating, by means of suitable connection devices, the required movements to the other mechanism.

The machine performs four functions— 60 namely: first, holds and feeds the fabric; second, picks up and feeds the buttons; third, makes the fastener; fourth, sets the fastener.

Though the making and the setting of the fasteners are distinct operations, which take 65 place one after the other, their mechanisms are so intimately associated as practically to form one.

The table on which the fabric F⁶ is laid is designated by U². This table forms one of 70 the caps for the fastener-making devices, and is secured to upright A³ by screws, as shown in Fig. 1. Said table has a driver channel or mortise, as at 2, Figs. 3 and 6, through which the fastener, after being made below said table, 75 is driven up into the fabric.

M is the feeding-bar, which is serrated at the lower end in the usual manner, (see Figs. 1, 12, 13, and 14,) and operates to feed the fabric after the manner of the ordinary four-motion 80 feeds commonly used in sewing-machines.

I do not limit my invention to the particular devices for producing that motion of bar M, but have shown one combination suitable therefor, which is the type of a class of such 85 devices.

As herein shown, the mechanism for operating the feeding-bar consists of the following: For producing the vertical movement thereof the upper end of the bar M is pivotally connected to an arm, V, which is fixed to rock-shaft S³, which shaft has another arm, V², whereby it is operated from C² by means of connecting-rod H⁴, having a pin, I³, working against said cam. This mechanism acts to lift 90 the feeding-bar, while a spring (not shown) serves to bring it down. For producing the lateral motion of that bar, a similar mechanism is employed, consisting of arm V³, having a pin, 3, working in a slot, 4, near the lower end 95 of said bar, a shaft, S⁴, to which said arm V³ is fixed, and which has another arm, V⁴,

whereby it is operated from cam C^3 by means of connecting-rod H^3 , having a pin, I^4 , working against said cam. This mechanism acts to move the feeding-bar toward the left-hand in Fig. 2, a spring (not shown) being provided to effect the return movement. The operation of this mechanism is as follows: At the end of one feeding operation the bar stands down at the left-hand, as in Fig. 2. Cam C^2 now turns shaft S^3 , lifting said bar as shown in Fig. 12. While the bar remains lifted cam C^3 allows a spring to turn shaft S^4 , swinging the bar to the right-hand, as in Fig. 13. Next, the cam C^2 allows a spring to lower the bar to the position shown in Fig. 14, where it is supposed to rest on the fabric ready to be again moved by cam C^3 to its position in Fig. 2 for the purpose of feeding the fabric. Buttons of the kind ordinarily used for shoes, or others similar, having shank substantially as shown, are thrown into hopper J , which is carried on a shaft, S^5 , which shaft is slowly revolved in bearing A^3 by gear G , fixed on said shaft and meshing with worm G^2 on shaft S . Running in bearings in uprights A^3 and A^4 is the shaft S^6 , which is rotated in the same direction as and more rapidly than shaft S by pulley P^3 , driven by belt B^2 from pulley P^2 on said shaft S . Rearward of upright A^4 said shaft S^6 is provided with a roller, R , fixed thereon, which corresponds with the grooved roller R' , which runs on studs N , projecting from said upright parallel to said shaft S^6 . These three rollers are arranged in a triangle, as shown in Fig. 4, and serve to hold in place and rotate a button-feeding spiral, W , which runs over roller R and under rollers R' . This spiral is formed of a wire or rod which is small enough to readily pass through the button-shanks, and it consists, substantially, of a cylindrical spiral terminating in an expanding spiral, 10, at its rear end. It will be obvious, on considering the matter, that if the cylindrical spiral is of a uniform size and pitch throughout its length it may not remain in the proper longitudinal position, as any slipping on its supporting-rollers would tend to move it endwise of them. To prevent this result, I have constructed said spiral with an additional improvement or modification, by which that portion thereof which runs between said rollers is made of a series of spiral and circular parts alternating in such manner that one or more of the circular ones will always be in contact with the rollers. The circular parts 6 are made round in cross-sectional form to fit into the grooves 7 of the said rollers, while the intermediate spiral parts, 8, are flattened so as to pass between surfaces 9 of said rollers. These points are shown best in Fig. 22. As the spiral revolves the hopper J also revolves, but much more slowly, thereby bringing all of the buttons into the track of point 11 of expanding spiral 10, which frequently, I may say generally, will pass through the shank of one or more buttons, which, being kept down by gravity, slide along on the wire spiral, as at 12, Fig. 3, until they

are carried under guides 13 and 14 of receiver K , the shanks projecting up through slot 15 in the top of said receiver. Guide 13 is made longer than 14, so that when two buttons are carried along on one turn of the spiral, as often happens, the shank of but one can enter slot 15, the other being pushed outside of guide 14, as illustrated in Fig. 20. The end W^2 of the spiral runs close to the upper side of receiver K , (see Fig. 3,) and is long enough to carry the buttons well into said receiver when it is not previously filled; but if this is the case, then said end W^2 springs back, as in Fig. 23, and drops the button into the hopper J . This action of said part W^2 not only disposes of the surplus buttons presented to the receiver, but also serves by its elasticity to push the buttons in said receiver through into the rear end, T^3 , of tube T . This tube T is telescoped at its rear end into upright A^4 , and at its front end is fixed into slide F and partakes of its reciprocating motion. Said slide has a button-channel, F^2 , a continuation of the one in said tube, leading down to the setting-die F^4 at the front end of the slide, as shown best in Figs. 3 and 18. The buttons are pushed forward, as aforesaid, by the button-feeding spiral through tube T , in which they are turned over by the spiral slot T^2 , and through channel F^2 to the position 16, Fig. 3, where they meet the button detent or spring F^3 , and when slide F is at its forward and normal position stand in front of the button-feeding pawl O , the point of which works through slot 17 in slide F , and is fixed to upright A^3 . If, now, slide F is moved rearward, said pawl O , by pushing against button 16, forces said button forward in said slide under the curved point 18 of detent F^3 , and when the slide moves forward it carries that button forward with its shank between the opposite parts of the fastener prong-bending die F^4 and directly over mortise 2 in table U^2 . At the same time another button is pushed forward of pawl O , as before. When one button is thus forced under spring F^3 , it forces the one previously there out of the front end of slide F , which, as we have seen, moves back off from said button, leaving it directly over mortise 2, ready to be carried away on the fabric.

Instead of spring-pawl O , I may employ a rigid finger supported on a pivot and operated by a light spring or other convenient equivalent means. Slide F derives its motion from cam C on shaft S , which cam acts on pin I^2 of lever H^2 , which is pivoted to the bed-plate at 20, and connected to said slide at 21.

D^2 and E designate, respectively, the driver-slide and bender-slide. Slide D^2 is provided with the driver D , and has a roller or pin, D^3 , which is acted upon by cam C^6 for the purpose of moving said slide up and down, as required. Slide E is grooved at E^2 to receive driver D , notched at E^4 to receive the wire, and E^3 to receive the end of former-pin Q , and is provided with a roller or pin, D^4 , whereby cam C^4 moves this slide in the required manner. Both of these slides lie in a recess in the

front of upright A³, slide D² being in front of E, and are held in place by cap U, which may be secured to said upright by screws, as shown in Fig. 2. Former-pin Q is immediately below table U², and is operated from cam C⁵, which acts on pin I of lever H, which lever is pivoted to the frame at A⁶, and at its upper end to said pin Q. It will be understood that the said cams are so shaped as to impart the proper motions to the said slides and pin, and that a similar understanding should also be had respecting the other cams of the machine, all which cams are always to be proportioned by the ordinary rules of mechanical construction, each to properly perform its special function.

R³ and R⁴ designate fastener-stock-feeding rolls, of which the lower one, R⁴, is fixed on shaft S⁵, having a pulley, P⁵, driven from pulley P⁴ by friction-belt B, the upper roll, R³, being supported on stud 22, which may be made adjustable for the purpose of tightening the rolls onto said stock, as now commonly done in similar cases. When slide E is lowered to its position in Fig. 6—slide D² being previously or simultaneously so lowered—the fastener-stock L feeds in through a hole in A³, as shown in Fig. 7. The former-pin Q now stands in its forward position, and the wire is next cut off by the ascent of slide E, as shown in Fig. 8, which slide then moves clear up, bending the wire into a staple, 24, as in Fig. 9. Slide D² now rises, and driver D forces the staple up through mortise 2 (see Fig. 10) until the points strike against die F⁴ and are clinched over, as in Fig. 11, after which the several parts of the fastener making and setting mechanism are returned to their former positions, ready for a repetition of this series of operations.

The operation of my improved button-setting machine will be readily understood from the drawings and the preceding description, being as follows: The machine having been constructed to make some specified kind of fastener, and to use said fasteners for setting a specified kind of buttons onto a fabric, as F⁶, a supply of said buttons is put into hopper J, and fastener-stock suitable for the making of said fasteners is fed in between rollers R³ and R⁴. The machine being started up by some one of the well-known appliances used for such purposes, is run long enough to bring a button to the setting-die, when the fabric is placed on table U² in proper position for setting thereon the first button. On the starting of shaft S cams C⁴ and C⁵ operate the fastener-making mechanism as hereinbefore described to make a fastener, which is immediately set by the fastener-setting mechanism as also hereinbefore described. While the fastener is clinching the fabric-feeding mechanism moves into the position indicated by Fig. 14, and, immediately said clinching is finished, slide F moves back, drawing the fastened button out of channel F², and the fabric is fed along to the proper position for

setting another button, which in the meantime, has been fed to the setting-die in the manner described. And thus the several operations of button-feeding, fastener-making, fastener-setting, and fabric-feeding may go on automatically as long as required.

I claim as my invention—

1. The combination of button-feeding mechanism, substantially as described, with button-fastener-setting mechanism and with mechanism, substantially as described, for making button-fasteners and presenting them to said setting mechanism, all arranged to operate substantially as shown and described. 75

2. The combination of button-feeding mechanism, substantially as described, with button-fastener-setting mechanism and with mechanism, substantially as described, for cutting off a piece of button-fastener stock and bending said piece into a button-fastener, ready to be set by said setting mechanism, all arranged to operate substantially as shown and described. 85

3. The combination of a table on which to place the fabric or material to which buttons are to be attached, said table having a driver-channel, through which a button-fastener may be driven into said material, a laterally-movable setting-die, substantially as described, above said table having its normal position directly over said driver-channel and having a lateral motion away from its said normal position, and a button-fastener driver, all arranged to operate substantially as described, and for the purpose specified. 90

4. The combination of a movable part having a button-fastener-setting die at one end and a button-channel leading to said die, a button-detent for holding a button in said channel at said die, and a button-feeding pawl for pushing along the button in said channel under said detent, substantially as described. 105

5. The combination, in a button-setting machine having a suitable frame-work, of slide F, having channel F², detent F³, and pawl O, substantially as and for the purpose set forth. 110

6. The combination of a suitable frame-work, slide F, having a button-channel, F², receiver K, and tube T, leading from said receiver to said channel, substantially as described. 115

7. In a button-setting machine, the button-receiver K, having guides 13 and 14, substantially as described. 120

8. In a button-setting machine, the combination of a button-feeding spiral having alternate spiral and circular parts, substantially as described, and a set of grooved rollers for holding and rotating said spiral, substantially as set forth. 125

9. The combination of a button-hopper, a button-feeding spiral, substantially as described, and means, substantially as described, for holding and operating said spiral to take buttons out of said hopper, substantially as set forth. 130

10. The combination of a button-feeding spiral, substantially as described, means, substantially as described, for holding and operating said spiral, and a button-receiver arranged 5 to receive buttons from said spiral, substantially as described.

11. The combination of a button-feeding spiral having an elastic termination, W^2 , means, substantially as described, for holding 10 and operating said spiral, and a button-receiver arranged to receive buttons from said spiral, substantially as described.

12. The combination, in a button-setting machine, of fastener-making mechanism for 15 bending up a piece of stock into a button-fastener, a laterally-movable setting-die, substantially as described, for bending over into hooks the prongs of button-fasteners, mechanism for taking the fasteners from the fastener-making mechanism and driving their prongs 20

through a fabric against said die, and button-feeding mechanism adapted to hold a button at said die so that the prong or prongs of the fastener will be driven through the shank thereof, and to then release the button, all arranged to operate substantially as described. 25

13. The combination, in a button-setting machine, of the fastener-making mechanism for bending up a piece of stock into a button-fastener, feeding devices for supplying the 30 stock to said mechanism, fastener-driving mechanism, the fastener-prong-clinching device, the button-feeding mechanism, and the fabric-feeding mechanism, substantially as described.

FRANCIS H. RICHARDS.
